Matthew Foster & William Van Fleet Inventors
Setting Patent

The Schedule referred to in the Setting Patent and making part of the same containing a description in the words of the said Matthew Foster and William Van Fleet of their improvement in constructing cisterns, reservoirs and walls for holding water, or any other liquid and for other purposes.

To all to whom these presents shall come: Be it known that Matthew Foster and William Van Fleet of Sullivan in the County of Madison and State of New York have invented a new and useful improvement in constructing cisterns, reservoirs and walls for holding water or any other liquid and for other purposes and that the following is a full and exact description of the construction of a cistern, reservoir or wall in which the said improvement appears...

1. The curved reservoirs or reservoirs for holding water or any other liquid, a lot of stones made longer or shorter according to the depth of the intended cistern or reservoir and so constructed that when they are set up in a circular form by joining their edges they constitute a pattern case, known which in the form of a like case but constructed the cistern or reservoir as follows after described these stones are wider known as common stones and as the center of the cistern is intended, and of course as every one will understand except the last stone to be set up so that the key stone which is wider at the top than at the bottom for the purpose of crowning it from the pattern case to have the wall so constructed as mentioned hereafter. Then stones forming the pattern case are placed upon the stones so as to obtain them in their places while supporting the wall, so they are secured in their places by blocks longer or shorter, or wedges or others as aforesaid, 2. If the pattern case is thus prepared for the spit for the cistern or reservoir in any of sufficient dimensions to contain it, the stones intended and any depth required. A number of stones are placed upon the bottom of the cistern or reservoir by means of

1492
Cement or mortar-bine and sand and gravel or stone or brick or
any hard substance made a coat of the mortar or cement thus prepared
and laid upon the bottom of the pit of sufficient thickness to cover
the stones and the pattern base is then set upon the stones
in the manner above described.

The pattern is placed on the wall is then constructed
around the base course on the outside by mortaring with mortar cement
or mortar-bine with sand and gravel or stone or brick or any hard substance
in any proportion to make the mortar cement great or punty. The mortar
cement great or punty to be of any consistency, and the small stones can
be stuck to it by any thickness. The pattern base when the sand is put
into it remains in the cement used in constructing the pattern, the
soil or base is sufficiently immovable when the key stone is loosened
and the whole pattern base removed. The pattern is then placed upon the
punta in any ordinary way.

3. An angular pattern base or a wall is joined by like materials you
proceed in holding out or any other liguid as for any other wall.

That is claimed as the improvement invented by the subscriber
in the above specification is first the pattern base made which is con-
-structed the pattern base or wall made secondly compensating the
angular base with substances of any kind, and then forming
a permanent hold by means of the pattern base.
